UNITED STATES PATENT OFFICE.

CHARLES ALGERNON PARSONS, OF NEWCASTLE-UPON-TYNE, ENGLAND.

TURBINE INSTALLATION.

1,207,070.

Specification of Letters Patent.

Patented Dec. 5, 1916.

Application filed December 16, 1912. Serial No. 737,025.

To all whom it may concern:

Be it known that I, CHARLES ALGERNON PARSONS, K. C. B., a subject of the King of Great Britain and Ireland, and residing at 5 Heaton Works, Newcastle-upon-Tyne, in the county of Northumberland, England, have invented certain new and useful Improvements in and Relating to Turbine Installations, of which the following is a specification.

10 This invention relates to turbine installations, its object being to provide an improved form.

15 The invention consists in a turbine installation in which a condenser situated in immediate proximity to a turbine is provided with preheating tubes so placed as to be impinged by the exhaust steam at high velocity.

20 The invention also consists in the improved turbine installation hereinafter described.

The accompanying drawing shows partly in section and partly in side elevation a turbine and condenser attached thereto in accordance with the present invention.

25 One method of carrying the invention into effect is described by way of example as applied to a turbine installation suitable for driving electric machinery, and having a high pressure and a low pressure turbine mounted upon the same line of shafting as an electric generator. The low pressure turbine, *a* which alone is illustrated in the accompanying drawing, is situated between the high pressure turbine and the generator, 30 and is supported partly by the foundation *b* of the high pressure turbine and partly by the foundation *c* of the generator.

35 Steam exhausted from the high pressure turbine enters the turbine, *a*, through side inlets, one of which is shown at *d*, and after flowing in opposite directions through the turbine, is discharged through exhaust passages, *f* and *g*, which unite in a single eduction pipe, *h*. The latter is formed integral with the turbine casing and conducts the exhaust steam to a condenser or to a pipe by which the condenser can be automatically by-passed in a known manner, and the exhaust steam delivered to a still lower pressure turbine, hot well or the atmosphere, as

desired. The eduction pipe, *h*, forming part of the turbine casing, projects downward between the foundations, *b* and *c*, into a space capable of accommodating a large main condenser, *k*.

55 The condenser, *k*, is bolted or otherwise rigidly attached to the downwardly projecting eduction pipe, *h*, and thus forms part of the turbine casing structure. In this way there are avoided expansion joints or other means adapted to allow of relative movement between the turbine, *a*, and the condenser, *k*, as are necessary in arrangements in which the condenser is situated below the turbine delivering the exhaust steam, but is fixed to a foundation.

60 In the above arrangement, the expansion due to heat is accommodated by the natural spring in the water and air pipes to and from the condenser, such pipes being provided with expansible joints in most cases, so that the total weight of the condenser is 65 taken by the turbine casing to which the former is rigidly attached.

65 The condenser may be directly attached to any turbine other than the lowest pressure turbine of an installation while more than one such condenser, each attached to a turbine, may be provided, arrangements being 70 made, if desired, for short-circuiting or bypassing one or more such condensers and allowing the exhaust steam or other working fluid to pass to a lower pressure turbine, hot well or to the atmosphere.

75 A suitable condenser is that illustrated in which the entering exhaust steam impinges upon two nests of condenser tubes, one of which is shown in section at *l* and thereafter upon two further nests or tubes, *m*, situated at a lower level after which 80 the water of condensation is withdrawn through openings *n* in the usual manner. The tubes in the upper nests, *l*, are arranged at the corners of squares, while those in the lower nests, *m*, in addition to being 85 pitched at a smaller distance apart, are spaced according to the well-known equiangular arrangement. The circulating water enters the condenser through the inlet, *o*, and then passes through the two lower 90

100

nests of tubes, m and then upward and through the upper nests of tubes, l , to the outlet, q , which is arranged at the same end of the condenser as the inlet, o .

5 If desired the degree of vacuum produced in the condenser may be increased by a vacuum augmentor or by wet and dry air pumps arranged in a known manner and connected to the main condenser by 10 suitable conduits provided with expandable joints, if necessary.

According to the present invention it is arranged that the feed water passing to the boiler or other steam generator shall be 15 preheated by the exhaust steam entering a condenser, for which purpose such water is preferably passed through a number of tubes situated at the inlet to the condenser and impinged upon by the exhaust 20 steam from the turbine to which such condenser is attached. As the exhaust steam has a considerable velocity, heat is readily transmitted therefrom to the feed water, and an increased economy thereby obtained.

25 According to the arrangement illustrated, the feed water is admitted by an inlet, r , to a conduit, s , between which and a similar conduit situated at the other side of the turbine the tubes, u , for pre-heating the 30 feed water are arranged, preferably parallel with the tubes in the condenser, k . The conduit, s , is by means of suitable partitions, divided into three sections, indicated by numerals 1, 2 and 3, while the second 35 conduit is divided into two sections. The feed water, on being admitted to section 1 of the first conduit passes by way of the tubes, u , to the first section of the second conduit from which it passes through more 40 tubes, u , to section 2 of conduit, s , then through the tubes, u , to the second section of the second conduit, and finally to section 45 3 of conduit s , from which it is withdrawn through the outlet, v . The boiler feed water may of course be passed across the inlet of the condenser, k , as often as is desired, and the feed water circulated in any desired manner by means of tubes or the like situated at the inlet of any suitable type of 50 condenser independent of how the latter is attached or situated relatively to the turbine delivering the exhaust steam.

Having now described my invention, what I claim as new and desire to secure by Letters Patent is:—

55 1. An elastic fluid operated plant comprising in combination a low pressure turbine, supporting means separated by a space which is bridged by the casing of said 60 turbine, a condenser receiving the working fluid discharged from the turbine, said condenser being situated in the space below the turbine, means by which the condenser is suspended from the turbine casing, and pre-

heating means partly within said turbine 65 casing adapted to be impinged upon by the working fluid passing from the turbine to the condenser.

2. An elastic fluid operated plant comprising in combination a low pressure turbine, 70 supporting means separated by a space which is bridged by the casing of said turbine, an outlet to said casing, a condenser, an inlet to said condenser receiving the working fluid discharged from the turbine, 75 said condenser being situated in the space below the turbine, means by which the condenser is suspended from the turbine casing, the outlet of said casing being in close proximity to said condenser inlet, and a 80 system of tubes arranged across the inlet to the condenser, said tubes conveying fluid which is preheated on account of the tubes being impinged upon by the working fluid entering the condenser. 85

3. In a turbine installation in combination, a turbine casing, a condenser rigidly attached to and forming part of said casing structure and feed preheating means situated at the junction of said casing and said 90 condenser.

4. In a turbine installation in combination, a turbine casing, a condenser rigidly attached to and supported by said casing and means whereby the kinetic energy of 95 the exhaust working fluid passing to said condenser is converted into heat, said means being situated substantially in the plane of junction of said casing and said condenser.

5. In a turbine installation in combination with a turbine casing, eduction means in said casing, feed preheating means adapted to simultaneously conduct to the feed heat from the exhaust working fluid of the turbine and convert the kinetic energy of the 100 exhaust fluid into heat and conduct it to the feed, said preheating means being situated partly within said eduction means and comprising two conduits, inlet and outlet means to said conduits, and tubes passing 105 from one of said conduits to the other of said conduits and across substantially the whole area of said eduction means.

6. In a turbine installation in combination, a turbine casing, an eduction opening 115 in said casing, a condenser rigidly attached by horizontal joint to the walls of said opening to form part of said casing structure, two horizontal conduits situated partly within said casing and partly within said 120 condenser, said conduits extending along opposite sides of said opening, an inlet to one of said conduits, and an outlet to the other of said conduits, horizontal tubes connecting said conduits, said tubes extending over 125 substantially the whole of said opening.

7. In a turbine installation a turbine casing, a condenser, an outlet to said turbine

casing, an inlet to said condenser, said outlet and said inlet being joined, whereby said condenser forms part of said turbine casing structure, and preheating means positioned 5 between said casing and said condenser and partly within said casing.

Dated this 4th day of December, 1912.

In testimony whereof, I affix my signature in presence of two witnesses.

CHARLES ALGERNON PARSONS.
